United States Patent

Des. 235,632
Patented July 1, 1975

235,632

CANOE

Frederick D. Blake, 3207 Montrose Road,
St. Paul, Minn. 55119

Filed July 23, 1973, Ser. No. 381,717

Term of patent 14 years

Int. Cl. D12—06

U.S. Cl. D12—63

FIG. 1

FIG. 2

FIG. 3

FIG. 5

FIG. 4

FIG. 1 is a side elevational view of a canoe showing my new design; the opposite side is a mirror image of FIG. 1;

FIG. 2 is a top plan view of the canoe of FIG. 1;

FIG. 3 is a bottom plan view of the canoe of FIG. 1;

FIG. 4 is a rear elevational view of the canoe of FIG. 1; and

FIG. 5 is a front elevational view of the canoe of FIG. 1.

I claim:

The ornamental design for a canoe, substantially as shown and described.
